Primary Examiner—Robert A. Delehanty*Assistant Examiner*—Mark Cavanna(74) *Attorney, Agent, or Firm*—Akin Gump Strauss Hauer & Feld LLP(57) **CLAIM**

The ornamental design for a vial adapter, as shown and described.

DESCRIPTION

FIG. 1 is a top perspective view of a vial adapter in accordance with my new design;

FIG. 2 is a bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a bottom plan view thereof; and,

FIG. 8 is a top plan view thereof.

The broken lines in the figures are for illustrative purposes only and form no part of the claimed design.
